United States Patent Office

Des. 191,350
Patented Sept. 19, 1961

191,350

SHOPPING CENTER

Alexander P. Horvat, Richmond Heights, Mo.
(7235 Glades St., St. Louis, Mo.)

Filed Apr. 19, 1961, Ser. No. 64,824

Term of patent 14 years

(Cl. D13—1)

FIG.3

FIG. 1 is a perspective view from an elevated position of a shopping center showing my new design,

FIG. 2 is a top plan view of my new design,

FIG. 3 is a side elevational view thereof, and

FIG. 4 is a side elevational view taken at an angle of 45 degrees to the side elevational view of FIG. 3.

I claim:

The ornamental design for a shopping center, substantially as shown.
